UNITED STATES PATENT OFFICE.

WILLIAM R. PETZOLD, OF BALTIMORE, MARYLAND.

DESIGN FOR A BOTTLE.

SPECIFICATION forming part of Design No. 17,119, dated February 15, 1887.

Application filed April 15, 1886. Serial No. 199,035. Term of patent 14 years.

To all whom it may concern:

Be it known that I, WILLIAM R. PETZOLD, a citizen of the United States, residing at Baltimore, in the State of Maryland, have invented and produced a new and original Design for Bottles, of which the following is a specification.

Figure 1 is a broad side view of my newly-designed bottle. Fig. 2 is a narrow side view of same. Fig. 3 is a horizontal cross-section of the bottle, these three views being deemed necessary to fully illustrate my design.

In cross-section the bottle is oval in shape—that is, considered in elevation, it has two broad sides, A, which are flat, or nearly so, and two narrow sides, B, which are half-round. The two broad sides have a plain surface, while the two narrow half-round sides have horizontal ribs or flutes c, which extend from the

plain surface of one broad side to the plain surface of the other broad side, and these ribs or flutes are close together, lying immediately one upon the other from the top to the bottom of the bottle.

I claim and desire to secure by Letters Patent—

The design for a bottle, consisting of the two narrow half-round sides, B, connected by two broad sides, A, and having horizontal ribs or flutes c, lying immediately one upon the other, as shown and described.

In testimony whereof I affix my signature in the presence of two witnesses.

WM. R. PETZOLD.
